Primary Examiner — Jennifer Rivard

(74) Attorney, Agent, or Firm — Blakely Sokoloff Taylor & Zafman LLP

(57) **CLAIM**

The ornamental design for the hand plate, as shown and described.

DESCRIPTION

FIG. 1 is a top front perspective view illustrating my new design.

FIG. 2 is a top plan view thereof.

FIG. 3 is a bottom plan view thereof.

FIG. 4 is a side elevation view thereof.

FIG. 5 is a side elevation view from the opposite side thereof.

FIG. 6 is a front elevation view thereof; and,

FIG. 7 is a rear elevation view thereof.

The broken lines shown in the drawings illustrate a portion of the hand plate and form no part of the claimed design.
